UNITED STATES PATENT OFFICE.

ROBERT HENRY MESTER, OF WEBSTER GROVES, MISSOURI.

PROTECTOR FOR DESKS.

1,390,370.

Specification of Letters Patent. Patented Sept. 13, 1921.

Application filed August 17, 1920. Serial No. 404,234.

To all whom it may concern:

Be it known that I, ROBERT HENRY MESTER, a citizen of the United States, and a resident of Webster Groves, in the county of St. Louis and State of Missouri, have invented certain new and useful Improvements in Protectors for Desks, of which the following is a specification.

My invention is an improvement in protectors for desks and the like, to prevent scarring and splintering of the desk edges, and of the chair when they are struck together, the protectors being arranged at such point on the desk edges that they will be engaged by the chair, to prevent injury to the desk or to the chair.

In the drawings,

Figure 1 is a perspective view of a desk having the improved protectors,

Fig. 2 is a perspective view of a protector removed,

Fig. 3 is a section on the line 3—3 of Fig. 2,

Fig. 4 is a section on the line 4—4 of Fig. 3.

In the present embodiment of the invention, the improved protector, which is of rubber, or like material, is shown in connection with a desk 1, the protectors being arranged on the corners of the pedestal 2 of the desk at the front thereof, at such height that they will be engaged by a chair when pushed against the desk.

Each of the protectors is of angular formation, consisting of similar portions 3 and 3^a, extending at approximately a right angle with respect to each other, and integrally connected, and each of the said portions is of greatest thickness at its junction with the other portions, gradually decreasing in thickness toward its free edge.

Each portion has openings 4 near its ends, for receiving screws, indicated at 5, for connecting the protector to the desk, and these openings, as shown in Fig. 3, are flaring, or counter-sunk, to receive the heads of the screws, and to leave said heads flush with the outer face of the protector.

Intermediate its ends, the protector is grooved transversely, both portions being so grooved, the grooves indicated at 6 extending from one side edge of the protector to

the other on the concave face thereof, and the grooves are separated from each other by a rib 7 of material which is left in forming the grooves. Thus the protector is partially hollow on its inner face, that is, on the face which abuts the surface of the desk, these hollows forming air pockets for increasing the resiliency of the protector.

In practice, the protectors will have a length of about 5 inches, and a width such that the portions 3 at the front do not interfere with the movement of the drawers. That is, each portion will have a width somewhat less than the parting strip at the side of the drawer openings.

I claim:

1. A protector of the class described comprising a body of yieldable material provided with wings having their inner sides formed with pairs of spaced grooves defining air pockets, and ribs disposed between said pairs of grooves, thereby separating the same, the portions of said wings surrounding said air pockets being adapted to flatly contact with the article to which the protector is secured for entirely closing said air pockets.

2. A protector of the class described, comprising a body of yieldable material provided with wings having their inner surfaces formed with pairs of spaced grooves defining air pockets, and ribs disposed between said pairs of grooves thereby separating the same, the inner sides of said ribs being flush with the inner surfaces of the wings, the portions of said wings surrounding said air pockets being adapted to flatly contact with the article to which the protector is secured for entirely closing said air pockets.

3. A device of the class described, comprising a body of yieldable material provided with a pair of wings gradually reduced toward their outer edges and formed in their inner sides with communicating grooves defining air pockets, said grooves being gradually increased in depth from the outer edges of said wings, the portions of said wings surrounding said air pockets being adapted to flatly contact with the article to which the protector is secured for entirely closing said air pockets.

4. A protecting device of the class described, comprising a body of yieldable material being approximately L-shaped in cross section and formed with wings having their inner sides provided with gradually deepened grooves defining shock absorbing air pockets, and ribs disposed between said grooves thereby separating the same, said wings being gradually reduced in thickness from their inner to their outer edges and 10 provided with attaching means, the surfaces of said ribs being flush with the inner faces of said wings.

ROBERT HENRY MESTER.
